CLAIM

The ornamental design for a cable management rack, as shown and described.

DESCRIPTION

FIG. 1 is a perspective view of a cable management rack; FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken lines in FIGS. 1-7 represent structure and boundaries that are not part of the claimed design, but rather show the environment in which the design is associated.

1 Claim, 6 Drawing Sheets
